US00D892141S

(12) **United States Design Patent** (10) Patent No.: **US D892,141 S**
Clifford et al. (45) Date of Patent: ** Aug. 4, 2020

(54) **DISPLAY SCREEN WITH GRAPHIC USER INTERFACE FOR A SURGICAL CONSOLE**

(71) Applicant: **Stryker Corporation**, Kalamazoo, MI (US)

(72) Inventors: **Steven Thomas Clifford**, Byron Center, MI (US); **Anna-Karin Soederstroem**, Morgan Hill, CA (US); **Sarah Garcia**, San Jose, CA (US)

(73) Assignee: **Stryker Corporation**, Kalamazoo, MI (US)

(**) Term: **15 Years**

(21) Appl. No.: **29/693,229**

(22) Filed: **May 31, 2019**

Related U.S. Application Data

(63) Continuation of application No. 29/602,196, filed on Apr. 28, 2017, now Pat. No. Des. 854,549.

CLAIM

The ornamental design for a display screen with graphic user interface for a surgical console, as shown and described.

DESCRIPTION

The FIGURE is a display screen with graphic user interface for a surgical console or a portion thereof with a graphical user interface.

The broken lines showing an electronic device illustrate environmental subject matter, whereas the broken lines showing a display screen and elements of the graphical user interface illustrate portions of the article. No subject matter depicted in broken lines form part of the claimed design.
